UNITED STATES PATENT OFFICE.

FRED A. JONES, OF CANTON, OHIO.

ROTARY DRIER.

Application filed March 24, 1928. Serial No. 264,548.

The invention relates to driers adapted for drying coal, slack or other material in a broken or finely divided state, and more particularly to a drier adapted to be located 5 around a tubular kiln whereby the waste heat radiated from the kiln may be utilized in the drying of the material.

The object of the improvement is to provide a drier surrounding a portion of an inclined rotary kiln, means being provided for charging material to be dried into the upper or higher end of the drier and for discharging the dried material from the lower end thereof, the waste heat radiated from the kiln 15 being utilized to dry said material.

The invention also contemplates the provision of a circulation of air through the drier to assist in the drying of the material and if desired, this air may be drawn from between 20 the kiln and the drier in order that the air may be heated before it enters the drier.

The above and other objects may be attained by providing a plurality of pockets surrounding a portion of an inclined rotary 25 kiln and disposed longitudinally thereof, means being provided for charging material to be dried into the higher end of each pocket and for discharging the dried material from the opposite end of each pocket, the pockets 30 being flared toward their lower ends, if desired, in order to assist in passing the material therethrough toward the discharge end; means being provided for circulating air through the pockets and, if desired, for drawing 35 the air from between the kiln and pockets and passing the same into the pockets.

An embodiment of the invention is illustrated in the accompanying drawings, in which

40 Figure 1 is a side elevation of the improved drier, showing a portion of an inclined rotary kiln around which the drier is mounted;

Fig. 2, a longitudinal sectional view of the same;

45 Fig. 3, a transverse sectional view taken on the line 3—3, Fig. 2;

Fig. 4, a similar view on the line 4—4, Fig. 2;

Fig. 5, a transverse sectional view through 50 the drier and kiln, showing a modified form of charging mechanism taken substantially on the line 5—5, Fig. 6;

Fig. 6, a section on the line 6—6, Fig. 5;

55 Fig. 7, a fragmentary side elevation of a modified form of drier with parts broken away for the purpose of illustration;

Fig. 8, a transverse section on the line 8—8, Fig. 7; and

Fig. 9, a similar view on the line 9—9, Fig. 7.

Similar numerals refer to similar parts throughout the drawings.

The inclined, cylindrical kiln shown generally at 1 may be constructed, supported and operated in any usual and well known manner. The improved drier to which the invention pertains is adapted to surround the kiln cylinder either near one end portion thereof as illustrated in Fig. 1 or at any other location upon the kiln.

In the construction illustrated in Figs. 1 to 4 inclusive, the drier may be in the form of a hollow, cylindrical drum, comprising the outer and inner shells 2 and 3 respectively, the inner shell being preferably spaced from the kiln cylinder.

The drum may be divided into a plurality of longitudinal pockets 4 by means of the radial partition walls 5 located between the inner and outer shells. These pockets may be closed at the upper or higher end of the drum by the end plate 6 provided with a plurality of openings 7, one of which communicates with each longitudinal pocket. To aid material in traveling through the pockets, they may be provided with diverging side walls.

The outer shell 2 may be connected to the end plate 6 as by the angular ring 8 and the inner shell may extend beyond the end of the outer shell and be connected to the ring plate 9 as by the angular ring 10.

Charging compartments 11, corresponding in number and location to the longitudinal pockets 4, are provided between the ring plates 6 and 9, the rear and side walls 12 and 13 respectively, of said compartments being all inclined downward toward the openings 7.

Any suitable means may be provided for charging the desired amount of material to be dried into each receiving pocket. As illustrated in Fig. 1, this means may comprise a platform 14 mounted above the charging end of the drum and beneath a feed hopper 15 which may contain the coal or other material to be dried.

A funnel 16 may be supported above the receiving compartments of the drum and any device such as the reciprocating pusher 17 may be timed with the drum so that as each receiving compartment is positioned beneath the funnel 16, a charge of material may be dropped thereon from the platform 14.

The opposite end of the inner shell 3 may be connected to a ring plate 18 as by the annular ring 19, said ring plate being supported upon the kiln cylinder in any suitable and 5 well known manner.

The outer shell 2 terminates at a point spaced from the end of the inner shell, thus forming an annular compartment 20 into which all of the pockets 4 discharge, this annular compartment being surrounded as by the hood 21 and being arranged to discharge into the chute 22 at the under side thereof.

A pipe 23 may be connected to the upper portion of the hood 21 for drawing air into 15 the receiving compartments 11 and through the pockets 4, the heated air with moisture from material dried being discharged from the pipe to a pulverizer, burner or other equipment, or otherwise disposed of.

20 If desired, the material to be dried may be charged into the drum in the manner shown in Figs. 5 and 6. With this construction, the overhead hopper and pusher may be dispensed with and a scoop 24 may be connected to each receiving compartment 11 and adapted to pick up the coal or other material to be dried from the trough 25 as the drier is rotated therethrough in the direction of the arrow shown on Fig. 5.

30 As shown in Figs. 7, 8 and 9, the pockets 4^a may be flared toward their discharge ends in order to facilitate the travel of the material to be dried from the receiving compartment toward the discharge end of each pocket.

35 These pockets may be separate units, as illustrated in these figures, instead of simply compartments within a drum as shown in the form of the invention above described, such spacing causing increased heating of the side 40 wall area advantageous to drying. These pockets may be supported spaced from the kiln cylinder 1 in any suitable manner and provided with the receiving compartments 11^a similar to those above described.

45 The lower or large ends of these pockets may all communicate with an annular discharge chamber 26. For the purpose of assisting in drying the material passing through the pockets, heated air may be taken 50 into the discharge ends of the pockets from a point between the cylinder and pockets as by the pipes 27, this heated air passing through the pockets and out of the receiving compartments thereof, thus flowing counter to the material in the pockets, this air carrying off the moisture given off in the drying process.

In order to circulate this air through the pockets, a hood 21^a may surround the receiving compartments, a pipe 23^a communicating therewith for withdrawing the heated, moisture-laden air and conveying it to a pulverizer, burner or other equipment, or otherwise disposing of the air.

55 A feed chute or hopper 16^a may commun-

icate with the hood 21^a for filling the receiving compartments with material to be dried.

A plurality of discharge openings 28, corresponding in number and location to the pockets 4^a, are located around the periphery 70 of the annular discharge chamber 26. Each of these openings is normally closed by a door 29 hinged as at 30 to the exterior of the annular chamber and provided with a spring 31 or the like for normally holding the door 75 in closed position.

An angular arm 32 is fixed to each of these doors and adapted to engage the upper edge 33 of the discharge chute 34 to automatically open each door and discharge the material 80 from the adjacent pocket, as the same reaches a position above the discharge chute.

In operating the drier, it should be understood that the material passing through the kiln has no connection with the material being dried in the drier. For instance, raw cement-making material might be passing through the kiln while coal is being passed through the drier for drying.

The operation of the kiln is in no ways connected with the operation of the drier, the kiln simply being used as a means for rotating the drier pockets to pass the material therethrough, and the radiated heat from the kiln being utilized in drying the material.

90 In the operation of the drier, as the same is rotated by the rotation of the kiln, the receiving compartment of each pocket is charged with a substantially equal amount of material to be dried with each revolution 100 of the device.

105 This material is progressed by gravity toward the lower ends of the pockets as the same revolve and air is passed through the pockets to further assist in drying the material, this air being, if desired, heated air drawn from around the exterior of the kiln as shown in Fig. 7.

With each revolution of the drier, a portion of the material from each pocket is discharged into the common discharge compartment and from the same into the discharge chute.

I claim:

1. In combination with an inclined rotary 115 kiln, longitudinal pockets surrounding the kiln, means for charging material to be dried into the upper ends of the pockets and for discharging the material from the lower ends of the pockets.

2. In combination with an inclined rotary kiln, longitudinal pockets surrounding the kiln, means for charging material to be dried into the upper ends of the pockets and for discharging the material from the lower ends 125 of the pockets, and means for circulating air through the pockets.

3. In combination with an inclined rotary kiln, longitudinal pockets surrounding the kiln, means for charging material to be dried 130

- into the upper ends of the pockets and for discharging the material from the lower ends of the pockets, and means for passing air through the pockets counter to the flow of the material.
4. In combination with an inclined rotary kiln, longitudinal pockets surrounding the kiln, means for charging material to be dried into the upper ends of the pockets and for discharging the material from the lower ends of the pockets, and means for withdrawing heated air from around the kiln and passing it through the pockets.
5. In combination with an inclined rotary kiln, longitudinal pockets surrounding the kiln, means for charging material to be dried into the upper ends of the pockets and for discharging the material from the lower ends of the pockets, and means for withdrawing heated air from around the kiln and passing it through the pockets counter to the flow of the material.
6. In combination with a rotary kiln, downwardly inclined, longitudinal pockets surrounding the kiln, means for charging material to be dried into the upper ends of the pockets and for discharging the material from the lower ends of the pockets.
7. In combination with a rotary kiln, downwardly flared, longitudinal pockets surrounding the kiln, means for charging material to be dried into the upper ends of the pockets and for discharging the material from the lower ends of the pockets.
8. In combination with an inclined rotary kiln, longitudinal pockets surrounding and spaced from the kiln, means for charging material to be dried into the upper ends of the pockets and for discharging the material from the lower ends of the pockets and means for withdrawing heated air from between the kiln and pockets and passing it through the pockets.
9. In combination with an inclined rotary kiln, longitudinal pockets surrounding and spaced from the kiln, means for charging material to be dried into the upper ends of the pockets and for discharging the material from the lower ends of the pockets and means for withdrawing heated air from between the kiln and pockets and passing it through the pockets counter to the flow of the material.
10. In combination with a rotary kiln, longitudinal pockets surrounding the kiln, means for charging equal amounts into one end of each pocket upon each revolution of the kiln, and means for discharging the material from the opposite end of each pocket.
11. In combination with a rotary kiln, longitudinal pockets surrounding the kiln, means for charging equal amounts into one end of each pocket upon each revolution of the kiln, means for discharging the material from the opposite end of each pocket, and means for passing heated air through the pockets.
12. In combination with an inclined rotary kiln, longitudinal pockets surrounding the kiln, a receiving compartment at the upper end of each pocket inclined toward the pocket, there being a restricted opening between the receiving compartment and the pocket, means for charging material into the receiving compartments and means for discharging the material from the opposite ends of the pockets.
13. In combination with an inclined rotary kiln, longitudinal pockets surrounding the kiln, a receiving compartment at the upper end of each pocket inclined toward the pocket, means for charging material into the receiving compartments and means for discharging the material from the opposite ends of the pockets.
14. In combination with an inclined rotary kiln, longitudinal pockets surrounding the kiln, a receiving compartment at the upper end of each pocket, a discharge compartment communicating with the lower ends of the pockets, and means for charging material into the receiving compartments, passing the material through the pockets, and discharging the material from the discharge compartment.
15. In combination with an inclined rotary kiln, flared longitudinal pockets surrounding the kiln, means for charging material to be dried into the upper ends of the pockets and for discharging the material from the lower ends of the pockets.
16. In combination with a rotary kiln, longitudinal pockets surrounding the kiln and provided with diverging side walls to aid material in traveling through the pockets, means for charging material to be dried into the upper ends of the pockets and for discharging the material from the lower ends of the pockets.

In testimony that I claim the above, I have hereunto subscribed my name.

FRED A. JONES.
